ATTORNEY

UNITED STATES PATENT OFFICE

JOSEPH RUSSELL MOÏSE, OF HOUMA, LOUISIANA

ADVERTISING DEVICE

Application filed April 23, 1930. Serial No. 446,646.

My present invention has reference to a new and novel construction of advertising devices, which includes a shaft having an angle end that is removably attached to the lower end of a support for an overhead fan, and which shaft has journaled thereon a spirally wound member which is substantially helicoidal and which affords a holder for an article to be displayed, together with a frame of rectangular formation whose upper and lower arms are centrally fixed on the shaft and whose vertical and upper horizontal arms have journaled thereon vanes, the holder and vanes being multi-helicoidal so that the rotation of the fan will effect a turning of the holder and a like turning of the vanes, with the result that a continuous and varied color display will be effected which cannot fail to attract attention to the device and the article to be advertised and which is arranged in the holder.

To the attainment of the foregoing the invention consists in the improvement hereinafter described and definitely claimed.

In the drawings:

Figure 1 is a side elevation of the improvement in applied position.

Figure 2 is a sectional view approximately on the line 2—2 of Figure 1.

Figure 3 is a detail elevation with parts in section to illustrate the manner in which the helical beams are journaled on the frame element of the improvement and have one of their ends contacted by an anti-friction member.

In the drawings the numeral 1 designates the depending support for an overhead fan 1'.

Connected to the lower end of the tubular support 1, through the medium of a two-part clamp 2 there is a substantially horizontally disposed arm 3, the arm being directed below the blades of the fan 1'. The arm 3 merges into a straight extension which affords a vertical shaft 4. The shaft 4, adjacent to its ends, provides journals for bearings on the upper and lower horizontal members of the substantially rectangular frame 5. Suitable means are, of course, provided for holding the bearings from longi-

tudinal movement on the vertical shaft 4. The frame member 5 is preferably of wire and there is journaled on the vertical parts or sides thereof helicoidal vanes 6. These vanes are of a length approximately equaling the sides of the frame and have their ends contacted by anti-friction elements such as spheres 8 which are fixed on the side members of the frame. There are also journaled on the upper horizontal member of the frame vanes 7 disposed to the opposite sides of the vertical shaft 4. These vanes have their ends contacted by anti-friction elements 9 similar to the elements 8.

Journalized on the vertical shaft 4 are the ends of an article holder 10. The article holder comprises a spirally wound strip of some light material which may be metal, celluloid or the like. It may be here stated that the vanes 6 and 7 are constructed of very light material and that the frame 5 is of comparatively light wire. The article holder 10 is of helicoidal volute formation and is designed to receive therein a package 11 to be advertised. The package is clearly visible through the convolutions of the holder 10. The convolutions of the holder 10 and the twisted elements comprising the vanes 6 and 7 are preferably variously colored and the colors of the vanes 6 and 7 are equivalent to those of the article holder 10. Such color cannot fail to attract attention to the article 11 in the holder 10. The turning of the blades of the fan 1' will direct air against the vanes 7 and 6 and against the holder 10, causing these elements to turn, and sustaining and bring any varieties of properly blended colors to the vision of the passerby so that his attention cannot fail but be directed to the article in the holder. The holder as well as the vanes are slowly turned on their respective shafts and with my improvement it will be noted that the only means for imparting motion to the parts thereof is the force of the wind which is created by the fan which is necessary in merchandise houses.

The construction and advantages of my improvement will, it is thought, be understood and appreciated so that further de-

tailed description will not be required. Obviously, I do not wish to be restricted to the precise details herein set forth and, therefore, hold myself entitled to make such changes therefrom as fairly fall within the scope of what I claim.

Having described the invention, I claim:

1. In an advertising device, a frame, a vertical shaft on which the frame is centrally journaled and said shaft having an upper offset arm to be fixed on a support for an over-head fan, helicoidal members journaled on the frame and an open article holder journaled on the shaft.
- 15 2. An advertising device including a substantially rectangular frame, a vertical shaft on which the frame is centrally journaled, said shaft having an upper offset arm to be fixed on a support for an over-head fan, spirally wound vanes journaled on the frame, an open article holder in the frame and having its end journaled on the shaft and said holder being spirally wound to produce a helico volute spiral.
- 20 25 3. In testimony whereof I affix my signature.
JOSEPH RUSSELL MOÏSE.
